[57] **CLAIM**

The ornamental design for measuring tape with attachable chalk line, as shown and described.

DESCRIPTION

FIG. 1 is a side elevational view of a measuring tape with attachable chalk line showing my new design;
FIG. 2 is a front elevational view thereof;
FIG. 3 is a top plan view thereof;
FIG. 4 is a bottom plan view thereof;
FIG. 5 is a second side elevational view thereof;
FIG. 6 is a rear elevational view thereof;
FIG. 7 is a front elevational view showing the chalk line and measuring tape separated for use;
FIG. 8 is a side elevational view of an alternate embodiment of a measuring tape with attachable chalk line;
FIG. 9 is a front elevational view thereof;
FIG. 10 is a top plan view thereof;
FIG. 11 is a bottom plan view thereof;
FIG. 12 is a second side elevational view thereof;
FIG. 13 is a rear elevational view thereof; and,
FIG. 14 is a side elevational view showing the chalk line and measuring tape separated for use.
